UNITED STATES PATENT OFFICE.

MAURICE DUMONT, OF AURORA, ILLINOIS.

CHECK DEVICE FOR LOOM PICKER-STICKS.

SPECIFICATION forming part of Letters Patent No. 711,698, dated October 21, 1902.

Application filed February 17, 1902. Serial No. 94,502. (No model.)

To all whom it may concern:

Be it known that I, MAURICE DUMONT, of Aurora, in the county of Kane and State of Illinois, have invented certain new and useful 5 Improvements in Check Devices for Loom Picker-Sticks; and I do hereby declare that the following is a full, clear, and exact description thereof, reference being had to the accompanying drawings, and to the letters of 10 reference marked thereon, which form a part of this specification.

This invention relates to check devices for the picker-sticks of looms, designed to absorb the blow of the shuttle on the picker-stick at 15 the outer limit of its throw and to there-through indirectly arrest the outward movement of the shuttle.

Among the objects of my invention is to provide a device of this character which will 20 prevent rebound of the picker-stick and shuttle when the shuttle is thrown outwardly against the picker-stick, so that the shuttle arrested thereby will stop at the outer limit of its movement and in contact with the 25 picker, whereby when the picker is returned or swung inwardly it will not pound upon the shuttle, but will gradually force the same out of the shuttle-box and throw it through the race in an even and uniform movement, and, 30 further, to prevent the breaking of the filling on the cop when the shuttle is thrown outwardly.

The invention consists in the matters hereinafter set forth, and more particularly pointed out in the appended claims.

In the drawings, Figure 1 is a fragmentary view of one side of the lay of a loom, illustrating the upper end of the picker-stick and my improved check device for limiting the 40 outward throw of the picker-stick and the shuttle. Fig. 2 is a horizontal section taken on line 2 2 of Fig. 1. Fig. 3 is a detail plan section taken through the picker-stick and the supporting-brackets for the check device, 45 said view also showing the check-strap partially in section. Fig. 4 is a partial end view of the device shown in Fig. 1. Fig. 5 is a fragmentary detail illustrating the means of connecting the spring with the check-strap.

As shown in said drawings, A designates as 50 a whole a part of the lay of a loom, embracing a shuttle-race B, reed C, and a picker-

stick D, which carries at its upper end on its inner margin the usual picker d. The upper end of said picker-stick extends through a 55 slot b, formed between guide-boards B' B' at the end of the shuttle-race.

B' designates a binder-board forming part of the shuttle-box, which is located at the end of the shuttle-race. Said binder is held in 60 place by means of an arm E on the end of a horizontal rotative spring-pressed protector-shaft E', suitably journaled in the lay-frame, the upper end of the arm bearing against the binder to hold the same in place and swinging outwardly to permit the binder to spread when the shuttle enters the box in a familiar 65 manner.

F designates a buffer, which is located at the inner end of the slot b and designed to 70 arrest the inward throw of the picker-stick. Said buffer may be made of any usual or preferred form and in the form shown is usually made of leather and is inclined on its outer margin to correspond with the inclination of 75 the picker-stick when the latter occupies its inwardly-inclined position.

Referring now to the construction of the check device which constitutes my present invention, G designates a flexible strap which 80 is attached at one end to a downwardly-projecting stationary arm or bracket G', fixed rigidly to the lower margin of one of the guide-boards B' and located near the outer limit of the throw of the picker-stick. Said strap is 85 attached at its other end to one end of a spiral contractile spring G² in any suitable manner, and the other end of which spring is connected with a part which has adjustable connection with the lay-frame. As herein shown, 90 said spring is attached to a rod G³, which has adjustable sliding connection with a bracket G⁴, extending downwardly from the guide-board B' opposite to the board to which the bracket or arm G' is attached. Said bracket 95 is provided with a horizontal opening through which said rod extends, and the rod is held in an adjusted relation to the bracket by means of a set-screw g extending upwardly through the bracket and impinging against 100 said rod. The spring is provided at its end with a hook g', which engages a suitable opening in the end of the strap. In order to prevent the strap tearing out at its end, it is re-

inforced by an added thickness g^2 of leather or other suitable material, around which the hook extends. The rod G^3 extends through the spring, and therefore serves as a guide 5 for the spring and prevents the same from sagging down when the spring is not under tension, which would be liable to cause breakage of the spring. The strap G , being attached to the vertical arm or bracket G' , retains an 10 edgewise vertical position, and as said strap is relatively short there is no tendency of the same to sag down or become slack. The adjustable connection of the rod G^3 with the bracket or arm G^4 enables the tension of the 15 spring to be varied to suit the force of the impact of the picker-stick thereagainst and also to take up any slack in the strap or spring which may occur during long usage of the device. Moreover, by reason of the fact 20 that one end of the strap is attached firmly to a bracket which is located closely adjacent to the point of rest of the picker-stick when at the outer limit of its movement and that the other end thereof is attached to a yielding 25 part, such as the spring G^2 , the latter end only of the strap yields when the picker-stick is thrown outwardly against the same. After said picker-stick is first brought into contact with said strap, therefore, and before the 30 movement of said stick, caused by the shuttle striking against the same, is entirely arrested the strap is caused to move or slide transversely across the margin of the picker-stick, and thereby create a frictional resistance, 35 which aids the spring in arresting the movement of the picker-stick and shuttle, whereby said parts are brought more gradually to a rest than if such frictional resistance were not present. Furthermore, this construction 40 materially aids in preventing rebounding of the picker-stick under the action of the spring, for the reason that, in the first place, the force of the blow of the shuttle is gradually absorbed by the spring and frictional resistance, 45 and, secondly, tendency of the parts to rebound is counteracted by the friction due to the slipping of the strap across the picker-stick, said friction lessening the abrupt reac-

tion of the spring, such as might in itself cause a rebound of the stick and the shuttle. 50 As a result of this construction the picker-stick is gradually brought to a rest and does not rebound, so that the shuttle when it reaches the outer limit of its throw is brought to rest in contact with the picker, and when 55 the picker-stick is again swung inwardly it acts through the picker to gradually start the shuttle on its inward throw and prevents pounding of the picker against the shuttle.

It will be understood that my improved 60 check device may be employed upon all styles or types of looms, and for this purpose the device may be modified to adapt the same to different looms.

I claim as my invention—

1. In a loom, the combination with a picker-stick, of a check device for limiting the outward throw of the picker-stick, comprising a looped strap which is located in the path of the stick, said strap being attached at one 70 end to a part rigid with the lay-frame, a spiral contractile spring to one end of which the other end of said strap is attached, and a rod to which the other end of said spring is attached, said rod having endwise-sliding, adjustable connection with the lay-frame for the 75 purpose of varying the tension of said spring.

2. In a loom, the combination with a picker-stick, of a check device for limiting the outward throw of the picker-stick, comprising a 80 looped strap which is located in the path of said stick and is attached at one end to a part rigid with the lay-frame, of a spiral spring connected with the other end of said strap, a rod to which said spring is attached, said rod being adjustably connected at one end with the lay-frame and extending through said spring.

In testimony that I claim the foregoing as my invention I affix my signature, in presence of two witnesses, this 25th day of January, 90 A. D. 1902.

MAURICE DUMONT.
